HOIST CHAIN SWITCH ACTUATOR

Donald Mayer King, Hitchin, England

Application November 18, 1950, Serial No. 196,457

Claims priority, application Great Britain
November 23, 1949

2 Claims. (Cl. 200—47)

1

This invention relates to hoists, cranes or the like and has for its chief object to evolve means suitable for application to an electrically operated hoist, crane or the like and adapted to prevent overhoisting or overlowering.

According to the invention in a hoist, crane or the like wherein the driving motor is controlled by a switch, the actuation of which is effected through the medium of an arm or the like capable of angular movement, a resilient member is associated with the arm or the like in such a manner as to be disposed in the path of a striker element carried by the hoist rope, chain or the like, the arrangement being such that at a predetermined point in the travel of said rope, chain or the like the striker element will be caused to abut against the resilient member thereby to effect movement of the arm or the like and hence of the switch into its "off" position. Preferably the resilient member comprises a coil spring which is so dimensioned and arranged that the hoist rope, chain or the like will pass axially therethrough.

In order that the invention may be clearly understood and readily carried into effect the same will now be more fully described with reference to the accompanying drawings in which:

Figure 1 is a side elevational view showing a part of a chain hoist incorporating mechanism for preventing overhoisting.

Figure 2 is a section on the line 2—2 of Figure 1.

Figure 3 is a side elevational view of a detail.

Referring to the drawings 10 denotes a hoist chain which is attached at one end to a hoist block and is passed around a sprocket 11 carried by said block, the free end of the chain carrying the usual load hook 12. In known manner the sprocket 11 is driven in one direction or the other to effect raising or lowering of the hook 12 by means of an electric motor (not shown) the operation of which latter is controlled by means of a switch housed within the casing designated 13. Constructional details of the switch contained within the casing 13 are generally known and one type of switch is known as a "control circuit limit switch" and is manufactured by the Igranic Electric Co. Ltd. of Bedford, England. The switch has an operating arm 14 associated therewith which is capable of a pivotal or angular movement to effect actuation of said switch. The arm 14 is a part of the switch constructed by the Igranic Electric Co. Ltd., and is provided with a spring for snapping it past a "dead centre" to the "off" position of

5 the switch when moved through a certain distance, and it is coupled by means of a link 15 to one of a pair of operating levers 16 and 17 which latter are mounted for pivotal movement together about a pin 18 carried by the hoist block and are disposed in spaced parallel relationship so as to be at opposite sides of the hoist chain 10. Pivotedly mounted on a pin 19 supported by the levers 16 and 17 is a coiled spring 20 which is so disposed and of such diameter that the hoist chain 10 will pass freely therethrough. The diameter of the spring 20 is preferably so chosen as to be appreciably larger than that of the chain 10 in order to allow for swinging of said chain during operation of the hoist or for a permissible amount of deviation from the vertical due to sideways or lateral pulling of said chain.

20 Located at the lower end of the spring 20 is an annular member 21 which is adapted to form a suitable guide for the chain 10 and also to provide a convenient abutment surface. Mounted on the chain 10 at a point adjacent the hook 12 is a striker plate 22.

25 Preferably the coiled spring 20 is enclosed within a sheath or cover of canvas, rubber or other suitable material as indicated at 23 in order to protect said spring from damage due to weather or other atmospheric conditions and also to provide for an improved appearance.

Finally the lever 17 is formed with a projection 30 24 adapted during normal operation of the hoist i. e. when the switch is in its "on" position and the levers are in the position shown in full lines in Figure 1, to abut against a stop 25 thereby to maintain said levers in the desired position.

35 When the hoist is operative and the switch is in its "on" position the mechanism above described will assume the positions shown in the full lines in Figure 1. On continued "hoisting" 40 the striker plate 22 carried by the chain 10 will eventually be caused to abut against the annular member 21 at the lower end of the spring 20 with the result that the latter will be compressed. The arrangement is such that a relatively slight compression of the spring 20 will cause an angular movement to be imparted to the operating levers 16 and 17 such latter movement being effective to cause an appropriate angular movement of the arm 14 sufficient to move the switch 45 into the "off" position with resultant cutting out of the hoist motor. Further compression of the spring 20 will still be possible and that will allow for a reasonable amount of overrun should the brake normally fitted to the hoist not be properly adjusted and furthermore it will

avoid the possibility of breakage of any part of the switch mechanism by overrunning caused either by maladjustment of the hoist brake or by variation in the operation of the latter due to varying loads on the hoist block.

In the preferred construction the arm 14 has a spring associated therewith which is adapted to urge said arm in the direction indicated by the arrow A on the drawing. The arrangement is such that on upward movement of the levers 16 and 17 in the manner above described the link 15 and the arm 14 will be brought into a "dead centre" position wherein the three pivot points (i. e. the pivot point of the arm 14, the connection between the arm 14 and the link 15 and the connection between the link 15 and lever 16) are in a straight line whereupon the spring associated with said arm will become effective to force the latter to the limit of its movement corresponding to the "off" position of the switch. By virtue of this arrangement it will be appreciated that the degree of movement of the levers 16 and 17 necessary to effect actuation of the arm is relatively small. The resetting of the switch into the "on" position may readily be effected by hand, an appropriate movement being imparted to the arm 14 or link 15.

Furthermore, when the device above described is incorporated in a hoist including two or more falls of chain, it will be appreciated that the striker plate or the like will be disposed adjacent the load hook or bottom block.

I claim:

1. In apparatus of the class described having a driven shaft adapted to impart a raising and lowering motion to a hoist chain for controlling a switch the actuation of which latter is effected through the medium of an arm capable of angular or pivotal movement, the provision of means for moving the switch automatically to its "off" position, such means comprising lever means arranged to extend transversely with respect to the hoist chain and so mounted as to be capable of a pivotal movement, link means connecting said lever means to the aforesaid actuating arm, a rigid stop adapted to co-operate with said lever means to maintain the same in a predetermined inoperative position, a coil spring supported for pivotal movement between said levers, said coil spring being so dimensioned and arranged that the hoist chain passes freely axially therethrough, and a striker element carried by said hoist chain and adapted at a predetermined point in the path of travel of the latter to abut against said coil spring thereby to impart an angular movement to said lever means sufficient to effect movement of the actuating arm and hence of the switch to its "off" position.

5 pivotal movement on said lever means, said coil spring being so dimensioned and arranged that the hoist chain will pass freely axially therethrough, and a striker element carried by said hoist chain and adapted at a predetermined point in the path of travel of the latter to abut against said coil spring thereby to impart an angular movement to said lever means sufficient to effect movement of the actuating arm and hence of the switch to its "off" position.

10 2. In apparatus of the class described having a driven shaft adapted to impart a raising or lowering motion to a hoist chain for controlling a switch, the actuation of which latter is effected through the medium of an arm capable of angular or pivotal movement, the provision of means for moving the switch automatically to its "off" position, such means comprising a pair of levers disposed in spaced parallel relationship at opposite sides of the hoist chain, said levers being capable of pivotal movement together about a common axis and one being operatively connected to the aforesaid actuating arm, a rigid stop with which the second lever is adapted normally to co-operate in such a manner as to maintain said levers in a predetermined inoperative position when said switch is in its "on" position, a coil spring supported for pivotal movement between said levers, said coil spring being so dimensioned and arranged that the hoist chain passes freely axially therethrough, and a striker element carried by said hoist chain and adapted at a predetermined point in the path of travel of the latter to abut against said coil spring thereby to impart an angular movement to said levers sufficient to effect movement of the actuating arm and hence of the switch to its "off" position.
